3 Claims, (Cl. 340—40)

This invention relates to methods and means for controlling traffic, and more particularly to traffic intersections and control of traffic therethrough.

One reason for the congestion on the roadways in cities and in rural areas is the buildup of traffic at oversaturated intersections. Oversaturation occurs whenever a stream of traffic approaching a traffic light becomes heavier than that which can be accommodated by the corresponding green portion of the traffic light. Various well-known solutions have been employed to relieve the oversaturated condition. For example, overpasses have been constructed which permit one stream of traffic to pass over the top of the other stream of traffic, thereby permitting two continuous streams of traffic to cross one another without delay. One apparent disadvantage of the overpass is the cost of construction, especially in cities where buildings and other structures would hamper the construction of an overpass.

Still another solution to the problem of the oversaturated intersection is the familiar traffic circle. Normally the circle is made sufficiently wide to accommodate at least two lanes of oneway traffic so that the vehicles entering the circle in the right hand lane do not slow down the vehicles already on the circle in the left hand lane. Frequently, the vehicle in the left hand lane must cross over the right hand lane in order to leave the traffic circle. This crossover, or weaving, is done in an unsupervised manner and safety is made to depend upon the skill and judgment of the individual drivers. Also, during periods of extreme congestion weaving toward various exits causes the traffic circle to "lock-up" blocking all movement of traffic.

Another problem associated with the traffic circle is that all traffic is deflected around the circle including those vehicles which intend to proceed straight ahead without changing course or direction.

It is an object of the present invention to provide an improved traffic intersection.

It is another object of the present invention to provide an improved method of guiding streams of traffic through an intersection.

It is a further object of the present invention to provide improved apparatus for synchronizing and controlling the flow of traffic through an intersection.

Still another object of the present invention is to provide methods and means for permitting streams of traffic to pass through an intersection without appreciable delay or high cost of installation of the intersection.

It is a further object of the present invention to provide methods and means for permitting streams of traffic to flow through an intersection without requiring vehicles to cross over, or weave between lanes.

These and other objects of the present invention are accomplished by providing a novel intersection complex including a number of main roads leading to a central intersection, and a peripheral road surrounding the central intersection and crossing the main roads forming a number of exterior intersections. Traffic lights at the exterior intersections divide the incoming traffic into first and second platoons. The first platoons are directed onto the main roads leading to the central intersection. By proper timing of these traffic lights the first platoons arrive at the central intersection at alternate times thereby

2

permitting continuous flow through the central intersection without delay.

The traffic lights at the exterior intersections deflect the second platoons onto the peripheral road in a common one-way direction. Once again the traffic lights are synchronized and timed so that the second platoons arrive at exterior intersections at alternate times with the first platoons which have passed through the central intersection thereby permitting uninterrupted flow through the exterior intersections.

The first and second platoons originating from the same stream of traffic entering the complex are reunited at the exterior intersections after the first platoons have traveled through the central intersection and the second platoons have traveled around the central intersection on the peripheral road. In this manner a larger number of vehicles are passed through the complex than that which can be accommodated by the central intersection.

This traffic intersection complex can be constructed using existing city streets. Any four rectangular blocks can be employed with the central intersection located at the center and the peripheral roadway surrounding the outside of the four blocks. No modification or other structural changes need be made to the roads.

A further feature of the present invention is the absence of any crossover or weaving between lanes, thereby improving the safety of the system.

The foregoing and other objects, features and advantages of the present invention will be apparent from the following more particular description of preferred embodiments of the invention, as illustrated in the accompanying drawings.

In the drawings:

FIG. 1 is a schematic diagram illustrating an intersection complex constructed in accordance with the present invention;

FIG. 2 is an electrical schematic illustrating the control circuit shown in FIG. 1 and the connections to one of the traffic lights shown in FIG. 1;

FIGS. 3 and 4 illustrate the connections to four traffic lights shown in FIG. 1;

FIGS. 5 through 9 are waveform diagrams illustrating the signals applied to the five traffic lights in FIGS. 2 through 4; and

FIG. 10 is a diagram illustrating another embodiment of the present invention which is an expanded version of the embodiment shown in FIG. 1 for accommodating a larger number of roads.

FIG. 1 illustrates an intersection complex including four main roads 11-14 leading to a central intersection 16a. A peripheral roadway 18 including segments 18a-18d surrounds the central intersection 16a and crosses the main roads 11-14 at four intersections 16b-e.

The peripheral road 18 surrounds four square blocks 20a-d with the intersection 16a located at the center. The top of the intersection complex shown in FIG. 1 is designated N (north), the bottom S (south), the left W (west), and the right side of the complex is designated E (east).

Located at the intersection 16a-e are traffic lights 22a-e, respectively. The traffic lights are 22 are operated by a control circuit 24 which synchronizes the operation in a manner to be described in detail with respect to FIG. 2.

In order to illustrate the general operation of the intersection complex shown in FIG. 1 the path of two streams of traffic entering from the north and west are described. In the illustrated embodiment the streams of traffic emerge from the complex in the same direction. The stream of traffic entering on the north is broken into two platoons 26a and 26b. The platoon of traffic may

include a number of vehicles determined by the distance between intersections 16a-e and the speed of the vehicles.

Platoon 26a is permitted to pass through intersection 16e under control of traffic light 22e. Other vehicles in the stream of traffic entering the complex on the north side are deflected onto road 18a forming platoon 26b. After a complete traffic light cycle to be described in detail with reference to FIGS. 5-9 another platoon 26a is permitted to pass through intersection 16e. In this manner the forming of platoons 26a and 26b is repeated over and over again, once in every light cycle.

The stream of traffic entering the complex at the west side is divided into two platoons 28a and 28b. Platoon 28a proceeds straight ahead, while platoon 28b is deflected to the right. The timing of traffic lights 22b and 22e is staggered so that platoon 26a arrives at intersection 16a and passes therethrough before platoon 28a arrives at intersection 16a. In this manner platoons 26a and 28a are interleaved at intersection 16a permitting a free flow of traffic without delay.

In a like manner the timing of traffic lights 22b and 22e is arranged so that platoon 26b travels through peripheral roadway 18a and arrives in time to cross at intersection 16b after platoons 28a and 28b have passed through and prior to the formation of another set of platoons 28a and 28b. Therefore platoon 26b is permitted to pass through intersection 16b without delay and continues on to intersection 16c.

At intersection 16c the platoons 26b and 28b are guided by traffic light 22c. Platoon 28b is permitted to pass through intersection 16c continuing on peripheral road 18c. Platoon 26b is deflected from peripheral road 18b to main road 12 in a direction away from central intersection 16a. At this time platoon 26b is reunited with platoon 26a after platoon 26a has passed through central intersection 16a and platoon 26b has passed around intersection 16a on peripheral road 18a and 18b.

The traffic entering the complex on the south and east side is controlled by traffic lights 22c and 22d in the same manner as the traffic lights on the opposite side of the complex. Since the complex is symmetrical the operation of the platoons formed at intersections 16c and 16d is exactly the same as that described at intersections 16e and 16b respectively. For example when platoon 26a arrives at intersection 16a a similar platoon formed at intersection 16c also arrives at intersection 16a. Traffic light 22a permits the southbound platoon and northbound platoon to pass through intersection 16a at the same time and prior to the arrival of the westbound platoon and eastbound platoon formed at intersection 16b and 16d, respectively.

Detailed Description

The details of the control circuit 24 are shown in FIG. 2. The traffic lights 22 are supplied with signals from control circuit 24 which operate the red, amber and green signal lights mounted on four sides of the traffic lights 22. A power supply 32 provides the current for illuminating the traffic lights 22. A battery 34 operates a group of relays R-I through R-IV and R-I_A through R-IV_A under control of a pair of switches 52 and 54.

Battery 34 provides current to wiper arms 52a and 54a which are connected to a common shaft 56 and rotate in a clockwise direction at constant speed.

As shown in FIG. 2 the wiper arm 52a supplies current to a segment S-II connected via a line 58 to relay R-II. Current flowing from battery 34 flows through wiper arm 52a, segment S-II, line 58 to an operating coil 42a which pulls a contact 42b closed. The closing of contact 42b causes power supply 32 to provide current on lines 60 and 62.

In a like manner wiper arm 52a passes over segment S-II and engages a segment S-III. Relay R-III is operated causing power supply 32 to provide a signal on a pair of

lines 64 and 66. Other segments of switch 52, designated S-I and S-IV, are connected to relays R-I and R-IV.

When wiper arm 52a turns a full circle about switch 52 one cycle of operation is completed during which relays R-I through R-IV are closed and opened in a sequential manner. In a like manner relays R-I_A through R-IV_A are closed and opened in a sequential manner. However the interval of time during which the latter relays are closed is small as compared to the quarter cycle intervals of operation of relays R-I through R-IV. This is due to the smaller size of the sectors on switch 54 designated S-I_A through S-IV_A. For example, sector S-I_A is only about one-tenth as large as the sector S-II. Sector S-I_A is located so that it makes contact with wiper arm 54a just prior to the time when wiper arm 52a engages segment S-II. Located in this manner segment S-I_A closes the contact of relay R-I_A during the last portion of the interval when the contact of relay R-I is closed.

Also shown in FIG. 2 are the details of traffic light 22a which include four faces designated with N (north), W (west), S (south) and E (east). When faces N and E are swung into place and traffic light 22a is positioned as shown in FIG. 1, traffic approaching intersection 16a from the north observes the face designated N. Likewise traffic approaching from the west, south and east observes faces W, S and E, respectively.

Each face of traffic light 22a includes a red, amber and green signal light designated R, A and G. The vertical arrow adjacent to the green lights directs approaching traffic to proceed straight through the intersection 16a. Other green signal lights in FIGS. 3 and 4 include a horizontal arrow pointing to the right directing the approaching vehicles to turn right at the associated intersections 22b-22e.

The signal lights on traffic light 22a are connected to one or more of the contacts of relays R-I through R-IV and R-I_A through R-IV_A. The red and green signal lights are connected to relays R-I through R-IV and the amber signal lights are connected to relays R-I_A through R-IV_A. All of the signal lights are connected to a common return line 68 which is connected to one side of power supply 32.

For example, a pair of red signal lights 60a and 60b are connected to relays R-I and R-II via a line 60. Therefore vehicles approaching intersection 16a in FIG. 1 from the north and south are stopped during stages I and II of the control cycle. At the same time a pair of green signal lights 60c and 60d also connected to line 60 are illuminated permitting east-west flow of traffic through intersection 16a.

During stages II and IV the red and green lights on the four faces of traffic light 22 are reversed in response to the signal on line 66. In between changes from green to red, the amber signal light on the associated face of traffic light 22a is illuminated for a brief moment to provide a caution or warning signal to the approaching vehicles. The amber signal lights are illuminated in response to the operation of relays R-II_A and R-IV_A which provide signals at the end of stages II and IV. The connections between the amber lights and relays R-II_A and R-IV_A are shown in FIG. 2. The unused terminals from the control circuit 24 in FIG. 2 are utilized in FIGS. 3 and 4.

In order to summarize the operation of traffic light 22 shown in detail in FIG. 2 a set of waveforms is provided in FIG. 5. The four stages of the operating cycle are designated with I through IV at the top. The upper three waveforms represent the signal applied to the lights on the north face of traffic light 22a. When the waveform is in the upper level the associated signal light is illuminated, while the lower level of the waveform indicates that the light is not illuminated. During the first and second stages the red lights on the north and south faces of traffic light 22 are illuminated while the green lights on the east and west faces of traffic light 22a are illuminated as

described above. The short illumination of the amber lights is represented by the narrow pulse-like waveforms.

As can be seen in FIG. 5 the red and green lights are alternately turned on and off thereby interleaving traffic at intersection 16a. Since the four stages of operation are equal in duration the full capacity of intersection 16a is divided between the approaching traffic on a 50-50 basis. That is traffic approaching from the north and south share the green light portion of the cycle equally with the traffic approaching from the west and east.

FIG. 3 illustrates the connections between control circuit 24 and traffic lights 22b and 22c. The outputs from control circuit 24 are designated with one or more of the numbers I, II, III and IV indicating the stage or stages during which power is supplied to the associated terminal. In addition the common return terminal connected to line 68 and a constant supply terminal are designated as such. The constant supply terminal is connected to the red lights on the south and east faces of traffic lights 22b and 22c respectively. Since peripheral road 18 shown in FIG. 1 carries only one-way traffic no further signal lights are required on these faces. Some of the faces of the traffic lights shown in FIG. 3 includes a green signal light having an arrow pointing to the right. When illuminated these signals direct the approaching traffic to make a right turn. For example the green light with an arrow to the right on the north face of traffic light 22b directs traffic approaching intersection 16b on peripheral road 18a to turn right onto main road 11 in a direction away from central intersection 16a.

The green light with the arrow to the right on the west face of traffic light 22b directs traffic approaching intersection 16b from the west to turn right on peripheral road 18b thereby forming platoon 28b.

FIG. 4 shows the connections between the traffic lights 22d and 22e and control circuit 24. The operation of traffic lights 22b-e is summarized in the waveform diagrams shown in FIGS. 6-9.

In order to illustrate the operation of traffic lights 22b-e the formation of platoons 26a and 26b at intersection 16e is described. A summary of the operation of traffic light 22e is shown in FIG. 9. During stage I and II traffic approaching from the north passes straight through intersection 16e. During this time a waveform 72 indicates that a green light 72a is illuminated. During stage III a green light 74a is illuminated as indicated by a waveform 74. Waveform 74 is at the upper level during only a single stage or 25% of the full cycle. Therefore the platoon 26b shown in FIG. 1 is only 1/2 the size of platoon 26a formed during stages I and II.

Platoon 26a continues to travel down main road 14 arriving at intersection 16a at the beginning of stage III. Referring to FIG. 5 it may be seen that the green light on the north face of traffic light 22a is illuminated during stages III and IV permitting platoon 26a to pass through. The time interval for each stage is chosen with regard to the distance between intersection 16e and 16a as well as the speed of the vehicles so that minimum delay is encountered.

Platoon 26b formed during stage III travels along peripheral road 18a and arrives at intersection 16b at the beginning of stage I. Referring to FIG. 6 the north face of traffic light 22b provides an illuminated green light with an arrow straight ahead permitting platoon 26b to pass through. Since platoon 22b must travel a greater distance during the time interval of two stages than platoon 26a travels during the same interval, the speed limit should be raised or other conditions should be provided for balancing the difference in distance traveled by platoons 26a and 26b.

Platoon 26b continues its travel past intersection 16b on peripheral road 18b arriving at intersection 16c at the beginning of stage III. Referring to FIG. 7, the west face of traffic light 22c provides an illuminated green light with an arrow to the right during stage III. Therefore

platoon 26b is deflected from peripheral road 18b onto main road 12 in a direction away from central intersection 16a. Platoon 26b merges in behind platoon 26a which passes through intersection 16c during stages I and III.

5 Traffic light 22c operates in the same manner as traffic light 22e with opposite faces exchanged. That is, the south face of traffic light 22c operate the same as the north face of traffic light 22e. Traffic lights 22b and 22d are similar in operation to traffic light 22e with two differences.

10 The first difference is that traffic lights 22b and 22c are delayed two stages behind that of traffic light 22e with regard to the platoons directed into the main roads 11 and 13. Platoon 28a shown in FIG. 1 is formed during stages III and IV while platoon 26a is formed during stages I and II. This may be seen by referring to FIG. 6 where a waveform 76 indicates that the traffic moving west on main road 11 passes through intersection 16b during stages III and IV. By delaying the formation of platoon 28a two stages with respect to the formation of platoon 26a, these platoons arrive at alternate times at intersection 16a.

15 The second difference in the operation of intersections 22b and 22d from intersection 22e occurs in the formation of platoon 28b. Platoon 28b is formed in stage II as illustrated by a waveform 78 shown in FIG. 6. The formation of platoon 28b is prior to the formation of platoon 28a as opposed to platoon 26b which is formed after platoon 26a. This difference is necessary in order to allow platoon 26b to pass through intersection 16b during stage I providing uninterrupted flow of traffic.

20 In summary a traffic intersection complex is shown in FIG. 1 having a central intersection 16a surrounded by a peripheral road 18. A portion of the excess traffic over that which can be handled by intersection 16a is deflected around the peripheral road 18. A control circuit 24 provides synchronization and control over traffic lights 22a-e so that uninterrupted flow of traffic is achieved.

Expanded Intersection

25 FIG. 10 shows an expanded version of the intersection complex shown in FIG. 1. Like designations are given to those roads in FIG. 10 which are the same as the roads in FIG. 1. Additional main roads 14' and 12' are added in FIG. 10 along with an extension 18c' and 18d' to the peripheral road 18. An additional central intersection 16a' is formed.

30 The operation of the complex in FIG. 10 is similar to that in FIG. 1. For example traffic entering the complex in FIG. 10 from the south at intersection 16c is divided into two platoons, one traveling straight through on main road 12 and the second platoon being deflected to the right onto peripheral road 18c. The platoon deflected onto peripheral road 18c follows a path through intersection 16c', main road 12', intersections 16a' and 16e' peripheral road 18d reuniting with the platoon traveling north on main roads 12 and 14 at intersection 16e.

35 Traffic approaching the complex from the south at intersection 16c' is divided into two platoons. The first platoon proceeds straight through on main road 12' and the second platoon is deflected onto road 18c'. These two platoons originating from the same stream of traffic are reunited at intersection 16e' after the first platoon has traveled through intersection 16a' and the second platoon has traveled through intersection 16d.

40 The operation cycle for the traffic complex shown in FIG. 10 is divided into six stages instead of four as in FIG. 1. The expanded number of stages is necessary in order to accommodate the complicated routing of traffic especially through intersections 16c' and 16e'.

45 While the intersection complex shown in FIG. 1 is able to increase the flow of traffic by 50% over the capacity of intersection 16a, the complex shown in FIG. 10 is capable of increasing the flow of traffic 33 1/3% over the capacity of central intersection 16a and 16a'. The size of the platoons deflected around the peripheral loops in FIG. 10

is $\frac{1}{3}$ the size of the platoons permitted to proceed straight through the complex, while platoons 26b and 28b described in FIG. 1 are $\frac{1}{2}$ the size of platoons 26a and 28a.

Further expansion of the complex over that shown in FIG. 10 can be accomplished by adding additional main roads. Each time the intersection complex is expanded the number of stages in the operating cycle is also increased. The number of stages is determined by the number of intersecting streams of traffic. For example, in FIG. 1, there are two streams of traffic approaching the complex from the north and west. The streams of traffic approaching in the opposite direction from the south and east need not be considered since they can be accommodated without effecting the number of stages. The actual number of stages is given by the formula $2N$ where N is the number of intersecting streams of traffic. In the case of FIG. 1, $N=2$. Therefore there are four stages in the operating cycle.

In the case of FIG. 10, $N=3$. Therefore six stages are required. Each additional stream of traffic added to the complex creates the need for two additional stages in the operating cycle.

The amount of increase of traffic handled by the intersection complex over that which can be handled by the central intersection, or intersections, is given by the ratio $1/N$, where N is the number of streams of traffic as defined above. In the case of FIG. 1, $N=2$ indicating an increase of 50%. In the case of the intersection complex in FIG. 10, $N=3$ indicating an increase of $33\frac{1}{3}\%$.

The embodiments of the present invention shown in FIGS. 1 and 10 employ the roadways surrounding square blocks in order to use existing streets. However it is apparent that the shape of the peripheral roadway 18 could be altered to fit existing streets other than rectangular shapes. For example an improvement could be made by having a straight path between intersections 16e and 16b in FIG. 1, thereby decreasing the distance traveled by platoon 26b and providing for a more uniform speed.

In addition to the advantage of employing existing roads, the present invention does not require vehicles to cross over or weave between lanes as can be seen by examining FIGS. 1 and 10.

Although the embodiment shown in FIG. 1 employs a 50—50 split in the service of traffic approaching central intersection 16a other proportions can be used if the traffic demands are unbalanced. Also, the traffic light 22a can be eliminated entirely if the vehicles maintain the same speed and platoon formation.

The embodiment shown in FIG. 1 does not permit traffic approaching the intersection complex to leave the complex at other than the prescribed exit at the opposite side of the complex. Right turns can be effected without interference with the operation. For example vehicles approaching the complex on the north becoming part of platoon 26b could leave the complex at intersection 16b by making a right turn without causing delays. However modifications of the control of traffic lights 22 would be

necessary in order to permit right or left turns at central intersection 16a or to permit vehicles to continue straight through intersections 16b—16e when right turns are indicated to be proper in the embodiment as shown in FIG. 1.

While the invention has been particularly shown and described with reference to preferred embodiments thereof, it will be understood by those skilled in the art that the foregoing and other changes in form and detail may be made therein without departing from the spirit and scope of the invention.

What is claimed is:

1. The method of guiding streams of traffic through a complex of roads including two main roads crossing at a central intersection and a peripheral road surrounding said central intersection and crossing said main roads forming four exterior intersections each said main road carrying a stream of traffic to said complex, said method comprising the steps of:

dividing each of said streams of traffic entering said complex at said exterior intersections into first and second platoons;

directing all of said first platoons into said main roads with alternately timed arrivals at said central intersection permitting said first platoons to pass through said central intersection without delay;

deflecting all of said second platoons onto said peripheral road in a common direction about said central intersection, the deflection being timed to permit alternate arrival of said first and second platoons at said exterior intersections opposite their point of division; and

uniting the first and second platoons originating from the same stream of traffic entering said complex along one of said main roads after said first platoons have passed through said central intersection and said second platoons have passed through said exterior intersections.

2. The method as defined in claim 1 including dividing said streams of traffic so that said first platoons fill the capacity of said central intersection without causing overlap in the time of arrival of said first platoons at said central intersection.

3. A method as defined in claim 1 including dividing said streams of traffic so that each of said first platoons contain no more than 50% of the capacity of said central intersection and said second platoons contain no more than 25% of the capacity of said central intersection.
